JAR SHOULDER, - KNUCKLE JOINT

Filed June 2, 1945

UNITED STATES PATENT OFFICE

2,568,060

JAR SHOULDER KNUCKLE JOINT

William H. Dumble, Bakersfield, Calif.

Application June 2, 1945, Serial No. 597,222

8 Claims. (Cl. 294—86)

1

This invention is a knuckle joint for deep well fishing tools.

Various kinds of tools are employed in deep wells to recover, if possible, loose or frozen apparatus or parts thereof from a well hole.

One object of this invention is to provide a knuckle joint, for fishing tools, which is wholly free from fragile pivot or pin connections between the elements of the joint and which is specially provided with powerful jar-strain sustaining shoulders.

A further object of the invention is to provide a hydraulic motor in the joint to effect its knuckling function. Another object is to provide a device in the assembly to control the flow of pressure fluid in the joint, preferably in the form of a flow-bean type of valve.

Also, an object of the invention is to provide a knuckle joint having from end to end of the assembly a continuous passageway for fluid flow and also for the introduction and operation of a macaroni tool string or other adaptable apparatus.

A desideratum is to provide a heavy duty, simple, substantial, practical, readily operative, reliable and highly compact knuckle joint.

A particular object is to provide a knuckle joint involving but three principal elements all relatively movable in the knuckling of the joint but which have no relative rotation.

The invention consists in certain advancements in this art as set forth in the ensuing disclosure and having, with the above, additional objects and advantages as will be made manifest in the following description of the herewith illustrative embodiment; it being understood that modifications, variations and adaptations may be resorted to within the scope, spirit and principles of the invention as it is claimed in conclusion hereof.

Figure 1 is an axial section of the joint showing the parts in alined position. Figure 2 is a detail, top plan of the closed bean valve. Figure 3 is a longitudinal section of the joint shell, certain parts being in elevation and in knuckled position. Figure 4 is a sectional detail showing the beam valve in full open position. Figure 5 is a top plan of the empty shell and showing its full ring jar shoulder. Figure 6 is a cross-section on line 6—6 of Fig. 1, looking down.

A housing shell 2 of cylindrical form has on its upper end a threaded coupling 3 for attachment to the next section of a well tool string (not shown) by which the shell may be lowered, raised, and rotated as desired, and supplied with fluid

2

for circulation or to actuate the joint as will be explained. In the lower portion of the shell is a transverse, circular, bore shoulder 4 pierced by a hole 5 having parallel, flat side walls 6. Tiltably and non-turnably fitted in this hole is a tumbler 7 the upper end of which has a more or less conic head 8. This head has a basal shoulder 9 which normally sets flat on the shoulder 4, as shown in Fig. 1, to take the strain when a load is applied 10 in the joint, or for jarring action on the tumbler.

The lower end of the tumbler hangs below the shell and has a screw pin or other suitable joint device 7' for attachment of desired equipment. The tumbler 7 is adapted to be readily tilted from the coaxial position, Fig. 1, to the inclined position shown in Fig. 3; the shell hole 5 being laterally enlarged at 5a for clearance, of the tipped body 7. The tumbler is tubular for mud circulation and for passage of small tools as needed.

Simple and reliable means are provided whereby to firmly tilt the tubular member 7 and solidly hold it tilted while the fishing function is carried on. To that purpose a hollow piston 10, having 25 external packing 11, is slidably fitted in the upper portion of the shell. The piston has on its lower end a transverse wedge 12 presenting an inclined face 13 to and across the upper end of the tumbler head 8; this being materially recessed at 14 to clear the wedge 12 as it descends with a lateral reaction thrust on the engaged top corner of the head 8. The wedge and the tumbler head are constantly interlocked against rotation, relatively, in the shell. When the piston moves down 35 the tumbler rocks on the point X of the shoulder 4, Fig. 3, as a fulcrum and the head 8 solidly jams on the near side wall of the shell. Meanwhile the lower end of the tumbler is canted well off to the opposite side of the lower end of the shell so that an applied tool equipment is orbited in a wide path while the joint assembly is bodily rotated by the driving tool string.

The piston 10 is motivated by hydraulic pressure head set up in the shell chamber and derived 45 from circulating mud or pump to tilt the tumbler. And while the piston is being driven down it is desirable that circulation be kept up in the hole, if possible. To this intent a dislodgeable choke device, in one form or another, is mounted in the upper end of the piston for the purpose of accumulating a hydraulic pressure head upon the piston. After the pressure has accomplished its function, to tilt the tumbler, the choke is suitably dislodged to make an enlarged clearance way. 50 Here shown is a block 15 fixed in the piston and

having a central port 16 in the lower end of which is snugly seatable the nose of a diametrically split plug or valve 17 having legs 18 pivoted at 19 in an annular nut 20 screwing in threads 21 in the bore of the piston. These legs are constantly outwardly pressed by springs 22.

The nose of the valve 17 has a small port 23, formed by the nose parts when these close into the block 15, acting like a flow bean to cut down the volume of liquid flow and set up a water head pressure on the piston. The nose of the valve 17 has suitable packing 24—24 to prevent leakage at its seat in the valve, and between the nose parts.

After the fish has been securely engaged and the tumbler has been pulled back into alignment by raising the tool string somewhat the valve 17 is dislodged so that the full area of its port 16 is available for fluid flow and for the passage of working equipment to further operate on the fish. Therefore, the top end of the valve 17 has a cross-kerf 25 to receive the nib of a tool T, Fig. 4, by which the valve and the legs thereof, and the nut 20 may be bodily rotated until the valve nose passes below the lower face of the block 15 whereupon the nose parts will be snapped open by the spring 22, Fig. 4.

Direct line of fluid flow from the piston 18 to the head of the tumbler 7 is effected by means of a wash pipe 26 packed at 27 in the bottom of the piston and having a pivot 28 suitably fitted in the bore of the tumbler head 8 to allow for relative tilting action of the latter. It will be seen that the main joint forming elements have central bores capable of readily passing work tools needed to operate on the fish after it has been worked into alignment by the attached fishing instrument (not shown).

What is claimed is:

1. A fishing tool joint assembly including a shell having an open lower end and an internal, annular jarring shoulder adjacent to its bottom, a tumbler having a body part including a tool pin and a head joined by a reduced neck confined by the pin and the head against axial shift and being guided and laterally tilttable in the lower end of the shell and said head lying flat on said shoulder under load tension on the assembly and the head fulcruming on one side of the shoulder during tilting action, said tool pin being rigid with the lower end of the body and extending below the shell, and means in the shell for tilting the said head off the shoulder; the lower end of the shell including an elongate, parallel wall bearing below said shoulder in which the tumbler body part oscillates and by which the tumbler is rotated with and by the shell.

2. A fishing tool, knuckle joint assembly including a tubular shell having an annular, internal squarely transverse seat forming shoulder near its lower end and flat, parallel side wall faces below the shell bore and said shoulder to form a guideway, and a tumbling joint member having a top end head with a flat, transverse bottom shoulder to set on said shell shoulder and connect the shell and said member to transmit jarring action and to operatively align the shell and said member, the tumble member being tiltably guided and held against rotation between said faces, and means operative in the shell to engage said head and rock the said member on seat 70

shoulder; the said member having a part on its lower end to engage the bottom of the shell and stop axial shift of the member upward in either tilted position or aligned position thereof.

5. A tubular shell having at its lower end an internal guide, a tool joint member pivotally supported in the shell at a level above said guide, the said member projecting down through and oscillating in the guide without relative rotation, and a hydraulically actuated piston in the shell and operative on said member to tilt it in the guide; said member having spaced stop parts at the ends of the guide to engage the same and prevent axial shift of the axially aligned joint member in the guide.

10. 4. The combination of claim 3; said piston having a head with an axial port, a choke including a set of elements seated and longitudinally adjustable in said port and forming a constrictive flow orifice from said port, means for axially shifting said elements in the port to vary the orifice, and means for automatically expanding said elements in and when clear of the said port.

15. 5. The combination of claim 3; said piston having a head with a port of a size to pass a tool apparatus, and a choke consisting of an expandable flow bean axially movable and seating in said port to control flow and expanding from the port when shifted therefrom to fully clear the port, and means in the piston for axially moving the said bean.

20. 6. In a fishing tool joint, a shell having in its lower end a bore outlet having parallel side walls forming a bearing and having a transverse shoulder at the top end of said walls and normal to the shell axis, and a tumbling joint member having a neck oscillatively fitted between said walls for rotational drive by the shell and having a head with a flat bottom shoulder normal to its axis and adapted to squarely seat on the shell shoulder for jar function and to suspensively align the said member, and a stop part on the bottom end of the neck to engage the guide when the said member is either in axial alignment in the shell or is tilted in the guide.

25. 7. In a fishing tool joint, a shell, a piston slidably mounted in the upper end of the shell, a dislodgeable choke in the piston to set up back pressure in the joint for motivation of the piston; said choke being bodily shiftable in the piston to clear its bore.

30. 8. The combination of claim 7; said choke including parts which automatically open when withdrawn from the normal choking position.

55. WILLIAM H. DUMBLE.
